HAIR WAVING CLAMP

Application filed October 28, 1930. Serial No. 491,683.

In the permanent waving of the human hair it is common practice to apply a number of clamps to selected portions of the hair, each clamp being so constructed and applied 5 as to subject the hair therein to the action of a suitable solution, and heat, whereby the treated hair is caused to maintain its wave for a long period of time. In applying this treatment steam is generated, and it is not unusual for the steam so generated to make its 10 way down through the clamp to the scalp of the person undergoing the treatment, resulting in more or less serious scalp burns.

It is the object of the present invention to 15 provide means whereby this condition may be satisfactorily overcome and the steam positively and effectively prevented from reaching the scalp.

It is another object of the invention to provide 20 a means of the character indicated that may be easily adapted for use on a clamp of any design, and one that will be economical to manufacture, simple in form and construction, easily applied, and highly efficient in 25 its practical application.

In the drawing:

Figure 1 is a plan view of a clamp in extended position, and embodying our invention.

Figure 2 is a side elevation of the same in 30 a closed position with the curling rod mounted therein.

Figure 3 is a sectional view on line 3—3 of Figure 2 with the curling rod removed.

Figure 4 is a fragmentary perspective illustration of another embodiment of the invention.

In the embodiment of the invention as herein disclosed we show at 1 and 2 two clamping 40 bars hinged together as at 3 and, when closed, locked together by a link and lever means indicated at 4. The brackets 5 and 6 form supports for the curling rod 7 which is disposed over the center of the device.

45 In the present case the base portions of the

bars 1 and 2 are similar in construction, comprising wood bars 8 and 9 having shoulders 10 and 11 formed therein in which are seated opposed rubber elements as 12 and 13. On the bottoms of the bars 8—9 are mounted 50 felt pads as 15—16.

The construction of these parts is such that when the bars are clamped together a groove as 17 is formed between them, longitudinally thereof and directly below the opposing faces 55 of elements 12—13.

In effecting our invention we provide a tube as 18 adapted to seat within the groove 17 and having a plurality of spaced orifices 19 formed therein in parallel relation to its 60 axis. The tube is disposed with the orifices 19 directed upwardly between the elements 12—13.

The tube 18 is closed at one end as at 20, and the other end, 21, is connected to a source 65 of air pressure not shown.

When the device is in use air under pressure is fed into tube 18 and discharged therefrom through orifices 19, where it passes upwardly between the opposing faces of the 70 clamping elements 12—13, effectually preventing steam from passing downwardly to the scalp, and condensing such steam as might make its way downwardly between the two clamping bars.

75 While it is desirable to seat the tube 18 snugly enough in the groove 17 to secure a direct upward movement of the air, yet the bars themselves together with the pads 15—16 and the scalp of the patient form a 80 substantially closed chamber whereby air discharged therein will find its easiest outlet upwardly between the bars as described.

In the embodiment of the invention shown in Figure 4 the clamping bar is made hollow 85 as shown at 22 with a connection for a supply tube at 23, and with discharge orifices formed therein as at 24. By means of this construction the desired results are obtained as hereinbefore described but without the 90

necessity of providing the separate tube 18.

It is to be understood, of course, that while we have herein shown and described but one specific embodiment of the invention, changes 5 in form, construction, and method of arrangement and operation, may be made within the scope of the appended claims.

We claim:

1. The method of preventing scalp burns 10 in the process of forming waves in the human hair by heating a solution thereon whereby steam is formed, which consists in forming a chamber under the hair close to the scalp and below the heated solution and discharging 15 air through the chamber outwardly and away from the scalp toward the hair being treated.

2. In combination, a hair waving clamp comprising a pair of hingedly connected 20 clamping members having a cross-sectional configuration such as to form a groove along the bottom edges of their meeting sides whereby to form a chamber when the clamp is placed on a head, and means disposed in 25 the chamber so formed adapted to discharge air upwardly between the said clamping members.
